United States Patent Office.

R. L. McGOWAN AND WALTER FLETCHER, OF ALLIANCE, OHIO.

Letters Patent No. 83,396, dated October 27, 1868.

IMPROVEMENT IN RAILWAY-SWITCH STAND.

The Schedule referred to in these Letters Patent and making part of the same.

To all whom it may concern:

Be it known that we, R. L. McGOWAN and WALTER FLETCHER, of Alliance, in the State of Ohio, have invented a new and useful Improvement in Switch-Stands; and we do hereby declare that the following is a full, clear, and exact description of the same, reference being had to the accompanying drawings, and letters of reference marked thereon, making a part of this specification, in which—

Figure 1 is plan view, and

Figure 2, an end elevation.

To enable those skilled in the art to make and use our invention, we now proceed to describe its construction and operation.

Similar letters, in the drawings, refer to like parts.

This invention consists in the novel construction and combination of an elastic switch-lever with a notched slot in the switch-stand, and a sliding key, connected with the lever, whereby the switch is rendered self-locking, and is prevented from displacement by any accidental lateral pressure.

In the drawings, A represents a switch-stand, of ordinary construction, longitudinally of which, in the top, is a slot, a, through which passes the switch-lever c, made elastic.

Three or more recesses, a', open out of one side of the slot a, into either of which recesses the lever c

slips, as, in passing along the slot a, it comes opposite such recess.

In the drawings, the lever is shown as occupying the middle recess. When in this position, it is obvious that the lever is securely locked against any lateral pressure, and this, too, without the aid of bolt, bar, or pin, or any other device which may be displaced or lost.

To prevent the lever from displacement under transverse strain, we attach to it the sliding key b, which, when the lever slips into one of the recesses, falls, of its own accord, into the slot in front of the lever, and securely fastens it.

When the key is raised out of the slot, the lever may be sprung out of its recess, and be moved back or forth in the slot.

Having thus described our invention,

What we claim as new, and wish to secure by Letters Patent, is—

The lever c, in combination with the sliding key b, slot a, and recesses a', substantially as described.

In testimony that we claim the foregoing, we have hereunto set our hands, this 8th day of September, 1868.

R. L. McGOWAN.
